UNITED STATES PATENT OFFICE.

ALONZO LINTON BAUSMAN, OF SPRINGFIELD, MASSACHUSETTS.

COATING APPARATUS.

1,230,455.

Specification of Letters Patent. Patented June 19, 1917.

Application filed October 16, 1914. Serial No. 866,927.

To all whom it may concern:

Be it known that I, ALONZO LINTON BAUSMAN, a citizen of the United States of America, residing in the city of Springfield, 5 county of Hampden, and State of Massachusetts, have invented certain new and useful Improvements in Coating Apparatus, of which the following is a specification.

This invention relates to an improved machine for coating candies, cake, and the like, with a chocolate or other suitable covering.

The object of the invention is to provide an improved machine of the kind referred to, in which the coating operation in general 15 is automatic, and characterized broadly by the improved control of the coating material applied to the goods to be coated.

More specifically, the object of the invention is to provide a coating apparatus having a conveyer to carry the goods, means to positively feed a sheet or ribbon of coating material on the goods carried by the conveyer to cover the same.

Another object is to provide in such a machine means to synchronize the flow of an unbroken sheet of coating material and the conveyer so that the former will be laid on the conveyer in a predetermined and uniform manner.

Another object is to provide for the feeding of two sheets of coating material to the conveyer in the manner just described and further means to feed goods to the conveyer between the two sheets so that the latter, 35 being in a plastic condition, will completely envelop the goods in a predetermined and uniform manner.

Another object is to provide in a coating machine a conveyer for the goods, means for 40 positively feeding a continuous sheet or ribbon of coating material upon the conveyer at a point preferably close to and just before that at which the goods are fed to the conveyer, a second positive means for feeding a 45 continuous sheet of coating material upon the top of the goods to extend beyond the sides thereof at a point preferably close to and immediately after that at which they are fed to the conveyer, so that the sheets of 50 coating material will be applied to the bottom and settle over the top and sides of the goods at about the same time and a homogeneous and uniform coating that completely envelops each individual piece of the 55 goods coated will result.

Further objects are to improve coating

machines generally. All the objects will appear in the detailed description and annexed claims.

For the purpose of illustrating one preferred embodiment of the invention, reference is had to the accompanying drawings and description.

In the drawings:

Figure 1 is a plan view of the apparatus 65 with parts broken away to better show the interior construction.

Fig. 2 is a side elevation with parts broken away.

Fig. 3 is a front elevation showing the top 70 of the casing in vertical section and the pump casing broken away to indicate the manner of pumping the chocolate.

Fig. 4 is a diagrammatic view showing the conveyer, the nozzles feeding the sheets of 75 coating material thereto, the means for feeding the goods to be coated between the two sheets and the general coating operation.

Fig. 5 is a detail sectional view of the goods on the conveyer after they have been 80 coated.

Fig. 6 is a cross sectional view of one of the nozzles.

Fig. 7 is a front elevational view of one of the nozzles.

It is to be understood that the drawings are not intended as working drawings but only as illustrations of one preferred form of the apparatus such as will enable one skilled in the art to make and use the invention.

Referring to Figs. 2 and 3: the base of the apparatus is indicated by *a* which supports the tank *b* containing the main supply of coating material. The tank *b*, as customary in machines of this character, is provided with a heating jacket for maintaining the coating material at the desired temperature and is open at the top. Mounted above the tank *b* is a heat-retaining casing *c* and 95 extending therefrom is a supplemental casing *d*. Within the casing *c* and immediately above the tank *b* is mounted a wire belt or conveyer 10. Leading into a transverse slot in the front part of the casing is a conveyer 100 11 indicated diagrammatically, which delivers the goods to be coated to the conveyer belt 10. Another conveyer 41 receives the goods from the conveyer 10 and carries them to the rear of the machine through the heat 105 retaining casing *d* attached to and communicating with the casing *a*.

The main driving shaft of the apparatus is indicated by 1 and is connected by means of driving chains to the pump shaft 8 and the vertically arranged shaft 23 by a bevel gear connection with shaft 2. Power is transmitted from the latter to the vertical shaft 3 by means of a speed controlling mechanism 4 of a well-known form in which any pair of the intermeshing gears may, as desired, be connected by means of the clutch 5. The gears on the shaft 23 are all loose thereon and the gears on the shaft 3 are all keyed thereto. The clutch 5 shifts a key not shown, to connect any one of the gears on the shaft 23 to rotate therewith according to the speed desired. The shaft 3 is connected to the horizontal cross shaft 6 on which is a driving roll provided with teeth adapted to engage and drive the conveyer 41 around the suitably mounted guiding members 15, 16 and 17. A similar roll on shaft 7 is driven by means of an idler meshing with gears on shafts 6 and 7 (see Fig. 1) to drive the conveyer 10 which passes around the anti-friction guide members 12, 13 and 14. A conveyer belt 11 driven in any suitable manner feeds the goods to be coated to the conveyer 10 and the coating material is spread on to the conveyer in the following manner:

Referring to Fig. 3; it will be seen that the pump casing *f* has a common inlet from the coating tank *b* to the two gear pumps 24 and 25 contained in separate compartments 35 of the casing, each of which has a separate outlet, as by means of pipes 26 and 27 respectively. The pipe 26 leads upwardly to an adjustable nozzle mechanism 31 (see Fig. 2) through the connecting means 30. The pipe 27 leads upwardly to a similar adjustable nozzle mechanism 32 through the connecting means 29. In each of the pipes 26 and 27 is provided an overflow pipe 39 and 28 in each of which a valve is provided to control the amount of overflow.

The nozzle mechanism 31 is preferably arranged so that the outlet thereof is immediately adjacent the upper vertical travel of the conveyer 10 and at an angle thereto which may be adjusted as desired. The nozzle mechanism 32 is mounted to be angularly adjustable by means of a bracket 37 in which is a curved slot engaged by a binding device 38 to hold the extension 29 to the nozzle mechanism 32 in the desired angular position which is preferably at an acute angle with the upper travel of the conveyer 10. These nozzle mechanisms are constructed essentially in the same way and the adjustable means as by bracket 37 and 38 may be of the same kind for each extension 30 and 32.

Referring to Figs. 6 and 7; the nozzle comprises a casing 31 having a longitudinal slot 52 the length thereof, approximately the

width of the conveyer 10. The width of the slot is controlled by means of section 42 of the casing 31 which is held to the casing 31 by means of a flexible spring plate 43, one longitudinal edge of which is bound to the section 42 and the other longitudinal edge of which is bound to the casing 31. Two arms 44, near the sides of the section 42 are mounted integral therewith, and are each engaged by one of two adjustable stop members 46, threaded in brackets 45, one at each side and integral with the casing 31. By turning the stop members 46, the section of the nozzle 42 may be forced inwardly or be allowed to spring outwardly, due to its flexible connection with the casing 31 and thus the width of the nozzle opening may be adjusted as desired. By this means the thickness of the sheet of coating material emitted from each nozzle may be controlled accurately.

With the parts adjustable and arranged substantially as shown in Fig. 2, the apparatus is ready to operate. The pumps 24 and 25 in casing *f* positively force the coating material from the tank *b* through the pipes 26 and 27 to the nozzles 31 and 32 respectively. Nozzle 31 emits a sheet of coating material (see Fig. 4) *y* on to the conveyer 10, of a width approximately the same as the conveyer, at a point just before the goods *p* are fed to the conveyer 10 by means of the conveyer 11. Thus the goods *p* ride on the coating material *y* and are bottomed by the coating material. At very nearly the same point at which the goods are fed on to the conveyer 10, the nozzle mechanism 32 emits a sheet of coating material *k*, which is approximately the width of the conveyer 10, and which is directed or spread on to the conveyer and on to the pieces of goods *p*, the sheet of coating material *k* (see Fig. 4) being in a plastic state will then settle around the four sides of each piece *p* to join with the bottoming sheet *y*, thus completely covering each piece in a homogeneous envelop. The conveyer 10 is preferably made of wire and suitably formed so that it will hold the bottoming sheet of coating material *y* without allowing it to fall therethrough. When the pieces completely coated are transferred from the conveyer 10 to the conveyer 41, (see Fig. 2), the sheets but not the envelops, are broken and the excess coating material flows through the conveyer to be directed back to the coating tank *b* by any suitable means.

When on the conveyer 41 the goods are agitated in order that the excess coating material between the pieces may be broken and shaken through the openings in the conveyer 41 and be returned to the tank *b*. The agitating mechanism for thus individualizing the coated goods is indicated in Figs. 1 and 2 and comprises a frame 19 piv-

oted on the cross bar 17', mounted in the supplementary casing *d* under the conveyer 41. The frame 19 comprises the longitudinal side members, as indicated and a cross connecting member underlying the belt. On the side pieces 19 are mounted brackets 21 which have a part extending over the ratchet wheels 20 mounted on the shaft 9, rotatably mounted transversely of the casing *d* (see Fig. 1). This latter shaft is driven by means of a chain and sprocket connection with the shaft 6. Bearing pins are mounted in the brackets 21 to bear against and be supported by and thus support the frame 19 by the teeth on the ratchet wheels 20. As the latter turn with the shaft 9, the teeth operate to rapidly throw the frame 19 up and down, and the cross member of the frame bearing against the under side of the conveyer agitates the latter for the purpose described. The casing *d* is braced by means of cross members *g* connected by longitudinal brace members *h* (see Fig. 1).

The preferred form of the invention and its general operation having been described, the principal advantages of the invention will now be briefly disclosed. The accepted and most generally used machine for coating goods today known involves a system of conveyers, material tanks, and casings broadly like that shown in the drawings. The means for feeding the coating material to the goods, however, is quite different. The prior devices generally used for this purpose involve means to flood the goods (after they have first been covered on the bottoms) with vertically descending streams of material as they pass along with the conveyer. By the improved means herein disclosed, the goods are covered by a continuous ribbon or sheet of coating material uniformly emitted from a nozzle under positive and predetermined pressure. The covering sheet travels at the same speed as the goods on the conveyer so there is practically no relative longitudinal movement of the goods and coating material when they meet. The coating sheet is, therefore, laid on the goods with uniform precision and of a definite predetermined thickness. The synchronizing of the sheet and the conveyer is obtained by the speed control for the conveyer driving devices by means of which the conveyer may be brought to the same speed as the sheet forced out of the nozzle. Any slight variation of speed between the two can be corrected by the valves in the overflow pipes 28 and 39 which will control the speed of the sheets from nozzles 31 and 32.

The fact that the coating material is fed by positive force pump action into the form of a sheet which envelops each piece of the goods allows a wide choice of coating ma-

terial. In other words, the coating material does not need to be carefully made up with a view to working properly in the coating apparatus. Under the practice heretofore, it has been necessary to use a coating material within narrow limits of quality and condition for the coating operations depended on the nature of the material and its selected condition to flow properly around the goods. In the case of chocolate coating, for example, a definite amount of cocoa butter (an expensive ingredient) was necessary or the coating operations were unsuccessful. By the use of this invention, a much smaller amount of cocoa butter may be used (an important condition for hot weather coatings), and the coating operations will still be successful.

To state the advantage of the invention broadly, it may be said that coating operations are reduced to a mechanical control to a degree not heretofore approached.

It is realized that the invention may be carried out in other ways than by the specific form of apparatus shown for the purpose of illustration. The invention is, therefore, defined by the appended claims rather than by the foregoing specific description of the form at present preferred.

What I claim is:

1. A chocolate coating machine, comprising, in combination, a conveyer for the goods to be coated and continuously operable measuring means to positively force an unbroken sheet of chocolate onto the conveyer, whereby the chocolate is laid on the sides and tops of the goods in a uniform and predetermined manner.

2. A chocolate coating machine, comprising, in combination, a conveyer for the goods to be coated, continuously operable measuring means to positively force an unbroken sheet of chocolate onto the conveyer, driving devices for the conveyer and means to synchronize the speed of the conveyer and the speed of the measuring means, whereby the chocolate is laid on the sides and tops of the goods in a uniform and predetermined manner.

3. A chocolate coating machine, comprising, in combination, a conveyer for the goods to be coated and continuously operable measuring means to positively force an unbroken sheet of chocolate onto the conveyer, means to feed the goods to be coated onto the sheet of chocolate carried by the conveyer, and other continuously operable measuring means to positively feed an unbroken sheet of chocolate onto the sides and tops of the goods in a uniform and predetermined manner.

4. A chocolate machine, comprising, in combination, a conveyer for the goods to be coated, continuously operable measuring means to positively feed an unbroken sheet

70

of chocolate onto the conveyer before the goods are placed thereon, and thereafter to positively feed a measured and unbroken sheet of chocolate over the sides and tops of the goods, whereby the two sheets of chocolate completely cover each piece of goods carried by the conveyer.

5. A chocolate coating machine, comprising, in combination, a conveyer for the goods to be coated, means to feed the goods to the conveyer, a continuously operable measuring device to positively feed an unbroken sheet of chocolate to the conveyer before the goods are fed thereto, a second continuously operable measuring means to positively feed a second unbroken sheet of chocolate to the conveyer and over the sides and tops of the goods after the latter are fed to the conveyer, and means to synchronize the speed 20 of the conveyer and said devices.

6. A chocolate coating machine, comprising, in combination, a conveyer, means to feed goods to the conveyer, continuously operable measuring means for positively feeding a continuous sheet of chocolate upon the conveyer at a point close to and just before that at which the goods are fed thereto, a second continuously operable measuring means for positively feeding a continuous 30 sheet of chocolate upon the sides and tops of the goods at a point close to and immediately after that at which the goods are fed to the conveyer.

7. A chocolate coating machine, comprising, in combination, a conveyer, continuously operable measuring devices for positively forcing chocolate in upper and lower sheets onto the conveyer at different points, so that they may be carried along by the conveyer, and means to feed the goods to be coated onto the conveyer between the points at which the sheets are fed thereto, whereby the goods are enveloped and surrounded by the chocolate.

45. 8. A chocolate coating machine, comprising, in combination, a conveyer for the goods to be coated, a chocolate tank provided with heating means, a nozzle extending adjacent to and transversely of the conveyer provided with a longitudinal outlet, a pipe connection between the tank and nozzle, a pump in said connection adapted to positively force the chocolate in a plastic condition through the nozzle and into an unbroken 50 sheet onto the conveyer, whereby the goods are coated by the chocolate in a uniform and predetermined manner.

9. A coating machine, comprising in combination, a conveyer for the goods to be coated, a tank for coating material, two nozzles each having longitudinal outlets extending transversely of the conveyer, means to connect the nozzles with the tank, and pumping mechanism to positively force the 60 coating material through each nozzle in an

unbroken sheet to coat the goods carried by the conveyer.

10. A coating machine, comprising in combination, a conveyer for the goods to be coated, a tank for the coating material, a nozzle mechanism having a longitudinal outlet therefrom, a pipe connection between the tank and nozzle mechanism, a pump in said connection to positively force the material from the nozzle, and means to adjust the 75 nozzle mechanism so that its longitudinal outlet extends transversely of the conveyer at a desired angle thereto and at a desired distance therefrom.

11. A coating machine comprising in 80 combination, a conveyer for the goods to be coated, a tank for the coating material, a nozzle having a longitudinal slot therein as an outlet, pipe connections between the tank and nozzle to positively force the material 85 through the outlet of the nozzle into a continuous sheet, said nozzle being arranged adjacent the conveyer with the outlet extending transversely of the conveyer, and having a spring mounted lip along one edge 90 of the outlet with means to force the lip against its spring mounting to regulate the transverse dimension of the outlet as desired.

12. A coating machine, comprising in 95 combination, a conveyer arranged to carry the goods to be coated along an upper horizontal travel, two nozzles each with a longitudinal slot therein, one arranged adjacent to and transversely of the vertical 100 travel of the conveyer just before it turns for its upper horizontal travel, the other arranged transversely and adjacent to the conveyer in its upper horizontal travel, a tank for the coating material, separate pipe 105 connections from the tank to each nozzle, and pump mechanism to positively force through each nozzle a continuous unbroken sheet of coating material onto the conveyer at different points, whereby the goods may 110 be fed to the conveyer between these points and be enveloped by the sheets.

13. A coating machine having in combination, a conveyer, a receptacle for coating material, a sheet forming device having a 115 converging outlet or nozzle one side of which is adjustable to control the thickness of the sheet, and mechanical means between the receptacle and nozzle to positively measure and force the coating material through the 120 nozzle forming device.

14. A coating machine having in combination, a conveyer, a receptacle for coating material, adjustable sheet forming devices provided with unobstructed outlets arranged 125 in spaced relation along and extending transversely of the conveyer, an article feeding device arranged to deliver goods to the conveyer between the outlets, a mechanical means between the receptacle and each sheet 130

forming device to positively measure and force the material through the outlets, and means to synchronize the speed of the conveyer to that of the measured sheets emitted 5 from the outlets whereby the goods will be covered.

15. A coating machine having in combination, a receptacle for the coating material, a conveyer, a sheet forming means, comprising an outlet or nozzle arranged transversely of the conveyer, a pipe connection between the nozzle and the receptacle, a positively acting measuring pump in the pipe connection, and means to drive the 10 pump and conveyer in properly timed relation to force the desired sheet on the latter.

16. A coating machine having in combination, a receptacle for the coating material, a traveling conveyer, a pair of sheet forming 20 devices, each comprising an outlet or nozzle arranged transversely of the conveyer and one in advance of the other in the direction of travel, pipe connections between said reservoir and the two nozzles, a positively acting 25 rotary measuring pump in each pipe connection, means for driving said pumps and conveyer in properly timed relation to force the two sheets of material on the conveyer, and means for feeding articles between said sheets.

17. A coating machine having in combination, a receptacle for the coating material, a conveyer movable from a substantially vertical plane into a substantially horizontal 35 plane, means for discharging a sheet of coating material upon the vertical stretch of said conveyer while moving, means for feeding articles on said coating sheet after it has turned into a horizontal plane, and 40 means for discharging a second sheet of

coating material upon the top and sides of the moving articles.

18. A coating machine having in combination, a receptacle for the coating material, a conveyer movable from a substantially vertical plane to a substantially horizontal plane, a nozzle extending across said conveyer having an adjustable outlet for discharging a sheet of coating material of regulable thickness upon the rising stretch of 45 said conveyer, while moving, means for automatically delivering articles onto said coating material at the turn of the conveyer, and a second and like nozzle for discharging a covering sheet of coating material 50 upon the top and sides of the moving articles.

19. A coating machine having in combination, a receptacle for the coating material, a conveyer movable from a substantially vertical plane to a substantially horizontal plane, a nozzle extending across said conveyer having an adjustable outlet for discharging a sheet of coating of regulable thickness upon the rising stretch of 60 said conveyer while moving, a belt conveyer terminating at the turn of the first conveyer for automatically delivering articles onto the horizontally moving sheet of coating material, a second and like nozzle for discharging a covering sheet of coating material 65 upon the top and sides of the moving articles, and a measuring pump between the receptacle and each nozzle for forcing the flow of the coating material in determined 70 quantities.
